UNITED STATES PATENT OFFICE.

WILLIAM LINDSAY, OF CHICAGO, ILLINOIS, ASSIGNOR TO L. WOLFF MANUFACTURING COMPANY, OF CHICAGO, ILLINOIS, A CORPORATION OF ILLINOIS.

ENAMELING-POWDER DISTRIBUTER.

1,273,632.

Specification of Letters Patent. Patented July 23, 1918.

Application filed August 12, 1912. Serial No. 714,491.

To all whom it may concern:

Be it known that I, WILLIAM LINDSAY, a citizen of the United States, residing in Chicago, in the county of Cook and State 5 of Illinois, have invented a new and useful Improvement in Enameling-Powder Distributers, of which the following is a specification.

This invention relates to improvements 10 in enameling powder distributers.

Hitherto, in sifting and distributing enameling powder over heated bath tubs or other vessels, the sifter or dredger has always, so far as I am aware, included a 15 body or vessel adapted to hold only a few pounds of the enameling powder at a time, which vessel or body has had to be refilled by hand when the supply became exhausted. On account of the high specific gravity of 20 the enameling powder and the fact that the sifter or dredger has to be held up by the operator and constantly moved about during the application of the powder to the tub or other vessel, it has been necessary to 25 limit the capacity of the body of the sieve or sifter to a comparatively small volume, with the result that the small amount of powder which can be placed therein is quickly used up and must be frequently re- 30 plenished. Inasmuch as the enameling powder has to be applied while the bath tub or other vessel is at a bright red to a white heat, it is essential that the operator apply the powder without any waste of time, but 35 where the operator has to frequently refill the containing vessel or dredger, not only is valuable time thus lost in the sifting operation, which allows the bath tub or other vessel to cool and requires additional firing, 40 but also the enameling powder is more or less unevenly applied, because the operator cannot tell each time exactly where he left off sifting before refilling.

An object of my invention is to devise an 45 apparatus which will overcome all of the objections above noted, and which is so arranged that the distributer proper may be continuously supplied with enameling powder from a reservoir tank while the operator 50 is applying the powder.

Another object of the invention is to provide means for feeding the powder with a constant even flow from the reservoir to the distributer.

55 A further object of the invention consists

in providing means for insuring the positive discharge of the enameling powder from the reservoir tank.

The invention furthermore consists in the improvements of the parts and devices 60 and in the novel combinations of parts and devices herein shown, described or claimed.

In the drawing forming a part of this specification, Figure 1 is a side elevation of an apparatus embodying my improvements. 65 Fig. 2 is a horizontal, sectional view, upon an enlarged scale, taken on the line 2-2 of Fig. 1. Fig. 3 is a vertical sectional view, upon an enlarged scale, taken on a plane passing through the axis of the reservoir. 70 Figs. 4, 5 and 6 are horizontal, sectional views, taken on the lines 4-4, 5-5 and 6-6 of Fig. 3, respectively. Fig. 7 is a side elevation showing my improvements embodied in a slightly different form of apparatus from that shown in Figs. 1 to 6 inclusive, parts being broken away to more 75 clearly illustrate the construction. Fig. 8 is a detail, sectional view of the valve members used in the construction shown in Fig. 80 7, and Fig. 9 is a detail, sectional view of a portion of the distributor handle, showing the manner of supplying compressed air to the interior thereof for forcing the powder therethrough. 85

In the drawing, A represents the powder distributer, which may be of the type shown in either of the patents issued to me, Nos. 939,918, dated Nov. 9, 1909 and 951,478, dated March 8, 1910, or of any other well 90 known construction. The powder distributer A, as shown, comprises a vessel or box and has secured thereto a hollow, tubular handle 20, which communicates with the interior of the box or vessel. At the outer 95 end of the hollow handle 20 is secured one end of a flexible pipe connection 21, the latter being connected at its other end to the discharge end 22 of the reservoir B. The reservoir B may be of any desired formation, but preferably comprises an upper, cylindrical portion 23, having a conical hopper bottom 24, the latter being provided at its lower end with a small chamber 25, the chamber 25 and the interior of the reservoir 100 being in communication with each other by means of the hole 26 formed in the top wall of the chamber 25. The reservoir B may be supported in any desired manner, for instance, as by means of the downwardly ex- 105 110

tending supporting wall 260, and adapted to be transported or handled by means of a bail 27 and handles 28. The enameling powder is adapted to be placed in the reservoir through an opening at the top thereof, which is normally closed, as by means of a pivoted cover 29, the latter having a cut-out portion at the center for a purpose presently to be described. The reservoir may be 10 made for any desired capacity, preferably of one hundred to one hundred and fifty pounds. As is well known, the specific gravity of enameling powder is comparatively high, and it has a peculiar tendency to "pack" or solidify, and 15 for this reason it is essential that means be provided which will insure the positive feed of powder toward the outlet and discharge therefrom, and such means are provided in the following construction. Located within 20 the chamber 25 is a horizontal sieve member 30, which is of rigid construction, and preferably of quarter inch mesh and is secured to a vertically reciprocating rod 310, the latter being cushion-supported at each end, as 25 by means of coiled springs 31, 32, the spring 32 being supported by a crow-foot 33 located within the discharge end 22 of the tank, and having an upwardly extending centering lug 34 for the coiled spring 32. Mounted on the 30 rod 31 and adapted to reciprocate bodily therewith are a plurality of tubular members 35, 36, 37, each secured to a common disk 40 at its upper end, said disk 40 being 35 flexibly secured to the rod 31, as by means of a coiled spring 41. The tubular members 35, 36 and 37, as shown, are concentrically arranged and are of varying lengths and diameters, the one of greatest diameter being the shortest and the one of smallest diameter 40 being the longest. The disk 40 is provided with a central recess 42 so that it may have a movement independent of the rod 31, and thus allow the tubular members 35, 36 and 37 to have an oscillating motion relatively 45 to the rod 31, as well as having a bodily reciprocating motion therewith. The lower edges of each of the tubular members 36 and 37, as will be obvious, will engage the enameling powder within the reservoir and will 50 scrape off a certain amount thereof when the same tends to pack and feed it down toward the bottom, the tubular members acting progressively to accomplish this result. The longest tubular member 35 is extended 55 slightly within the chamber 25 to thereby insure the positive discharge of enameling powder from the conical hopper 24 into the chamber 25. Any suitable means may be used for imparting a rapid, reciprocatory 60 motion to the rod 31 and the other members supported thereby, such means as shown comprising a pneumatically operated hammer 43, of any well known form, and adapted to be supplied with compressed air by 65 the pipe 44.

In order to force the powder through the hollow, tubular handle 20 in substantially a solid stream, compressed air is supplied thereto at its outer end as by means of the branch pipe 45, and at a plurality of points 70 intermediate the ends of the handle as by means of branch pipes 46, 46, leading off to the pipe 246, the direction of the discharge of air being, in each case, toward the distributor A, as more 75 clearly shown in Fig. 9. Where a sifter or dredger is used having a sieve bottom, means may be provided for imparting a rapid, vibratory motion thereto, and such means, as shown in Fig. 1, comprise a compressed air 80 turbine 47 adapted to be supplied from the branch pipe 48, said turbine being adapted to rotate at a high speed a shaft 49 on which is mounted, eccentrically, a disk 50. With such a construction, the powder distributor 85 A is caused to vibrate in the manner described in my said Patent No. 951,478. Compressed air for operating the pneumatic hammer 43, turbine 47 and for forcing the powder along the hollow, tubular handle 20 90 is supplied from any suitable source (not shown), through a pipe connection 51, the latter having a valve 52 therein, whereby the supply of compressed air to the various parts of the apparatus may be simultaneously governed.

In the construction of apparatus shown in Figs. 1 to 6 inclusive, the reservoir B is intended to be stationed at some point above the level at which the enameling 100 powder distributor is used, so that gravity will assist the powder in traveling along the outer supply pipe 21 to the handle 20 after the powder has been discharged from the reservoir, but should it be desired to have 105 the reservoir positioned at the same level as that at which the distributor is used, or even below the same, the enameling powder may be fed to the hollow, tubular handle by the construction shown in Fig. 7, where- 110 in compressed air is supplied to the cham- 115 ber 125 at the bottom of the reservoir B¹ and at various points along the powder feed tube 121, as by means of branch pipes 146, 146, leading out from the compressed air pipe 147. The discharging apparatus in the reservoir B¹ is operated by a pneumatic hammer 143 in a manner similar to the hammer 43, the same being adapted to be supplied with compressed air through 120 the pipe 144. The distributor, as shown in Fig. 7, comprises an inverted, funnel-shaped member A¹, in which case no sieve or screen is necessary at the bottom thereof. The distributor A¹, as shown, is also pro- 125 vided with a hollow, tubular handle 120 to which compressed air is supplied at the end thereof, as by means of a pipe 145, and at points intermediate the ends by branch pipes 148, 148. The supply of compressed 130

air to the hammer 143, powder feed pipe 121 and handle 120 is obtained from a pipe 151, and is governed by a valve 152.

In practice, the area of the sieve member 30 and the mesh thereof are so proportioned that the rate of discharge of enameling powder from the reservoir will correspond to the amount of enameling powder desired at the powder distributer, which may be at the rate of six pounds per minute. By employing compressed air to force the powder along the hollow, tubular handle of the distributer, the powder is moved substantially as a solid mass and flows out into the sifter or other form of distributer in a stream rather than being blown out in the form of light particles floating in air.

Various changes and modifications may be made in the parts of the apparatus without departing from the spirit of the invention, and all such changes and modifications are contemplated as fall within the scope of the claims appended hereto.

I claim:—

- 25 1. In an apparatus of the character described, in combination: a reservoir adapted to hold a quantity of enameling powder and having a discharge outlet; and means for discharging powder from the reservoir through said outlet, said means including a suspended reciprocating member adapted to have a constant oscillating motion about its own longitudinal axis to positively feed said powder toward said outlet.
- 30 2. In an apparatus of the character described, in combination: a reservoir adapted to hold a quantity of enameling powder and provided with a chamber at the bottom thereof and having also a passage therebetween, the chamber being provided with

a discharge outlet; and means for discharging powder from the reservoir into said chamber and from the chamber through said outlet, said means including a reciprocating sieve member located within the 45 chamber and a suspended member within the reservoir and adapted to have an oscillating motion.

3. In an apparatus of the character described, in combination: a reservoir adapted to hold a quantity of enameling powder and having a discharge outlet; and means for discharging powder from the reservoir through said outlet including a cushion-supported rod having a foraminous member secured thereto and adapted to be reciprocated, and a member secured to said rod above said member and adapted to oscillate relatively to said rod.

4. In an apparatus of the character described, the combination of a reservoir for containing enameling powder provided with a discharge outlet, and means for discharging powder from said reservoir through said outlet, said means including a 65 member of general tapering stepped form, the stepped parts of said member successively engaging the powder to advance it.

5. In an apparatus of the character described, the combination of a reservoir for 70 containing enameling powder and having a discharge outlet, and means for discharging powder from said reservoir through said outlet, said means comprising a vibratory member and a pneumatic hammer acting thereon.

WILLIAM LINDSAY.
